Primary Examiner — Austin Murphy(74) *Attorney, Agent, or Firm* — Calfee, Halter & Griswold LLP(57) **CLAIM**

The ornamental design for a holder, as shown and described.

DESCRIPTION

FIG. 1 is a rear/left/bottom perspective view of a holder (a rear/right/bottom perspective view would be a mirror image thereof);

FIG. 2 is a front/right/top perspective view thereof (a front/left/top perspective view would be a mirror image thereof);

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines show portions of the holder that form no part of the claimed design.
